DISPLAY DEVICE

Erskine D. Thompson, Burlingame, Calif., assignor to Standard Oil Company of California, San Francisco, Calif., a corporation of Delaware

Application November 7, 1934, Serial No. 751,803

2 Claims. (Cl. 40—96)

This invention relates to a display device for readily and quickly exhibiting a particular group of data or indicia from a number of such groups and more particularly relates to a lubrication and servicing data indicator in which groups of essential data and instructions are imprinted upon an endless web or belt which may be moved past a slot or window so that the particular group desired may be observed and correlated 5 with supplementary data on the face of the device.

Heretofore, in accumulating and presenting data for the proper lubrication and servicing of a complicated mechanism, such as an automobile, such data have either been printed on large charts of the alignment type, or upon 15 separate smaller cards or sheets which are bound into a book, strung upon wires or loops of cord, or otherwise assembled into one location for use. The large charts are not convenient because of the difficulty in quickly picking out the desired data from the large number of groups of figures, names, instructions and the like, thereon. Furthermore when they are in the smaller book or 20 loose-leaf form, so that the user must handle them, the single pages quickly become soiled and illegible from the grease and dirt that unavoidably accompany such servicing or lubricating operations. It is an object of this invention to 25 provide a means for conveniently and legibly displaying one particular group of data or indicia from a large number of the same, to correlate them with a supplementary group, and in such a manner that the whole will be protected from 30 becoming soiled or defaced by the operator, by the operations performed or by the weather.

Another object is to provide a means of the type described which may be easily changed from one group or class of indicia to another, without 35 handling or damaging the charts or surfaces carrying them.

Another object is to provide a display device in which the stationary chart as well as the movable element, each of which carries complementary parts of the data, are easily installed and removed for additions or alterations, and in which the said moving element is held in a secure and readable position with regard to the face of the device.

Another object is to provide a master chart or sheet bearing lubrication, identification, or servicing data on its face, and a relatively movable element bearing supplementary data, as for a given type or make of automobile, which latter 50 element may be aligned or correlated with the

master sheet in such a manner that the essential data desired, and none other, are readily observable.

These and other objects and advantages will be more fully apparent from the following description and from the accompanying drawings, which form a part of this specification and illustrate a preferred embodiment of this invention.

In the drawings:

Figure 1 is a front elevation view of a display device, showing the driving and idler roller and the web in place thereon, and illustrating the general type of indicia that may be placed on the cooperating parts.

Figure 2 is a vertical sectional view on line II—II of Figure 1.

Figure 3 is an end view of a preferred construction of a driving roller.

Figure 4 is a side view of a preferred construction of an idler and stretching roller.

Figure 5 is a view on line V—V of Figure 1 and shows a means for retaining the guide bar for the web.

Referring to the drawings and particularly to Figure 1, the numeral 10 represents a box or frame, which may be of light sheet metal, provided with brackets 11 for support on a wall or other flat surface. The front edge 12 of box 10 is preferably flanged as shown in Figure 1, and also provided with means forming a groove or channel 13 (Figure 2) so that a flat sheet or card 14 can be inserted to form a removable front closure for the box as well as a chart for data.

Sheet 14 is imprinted with data or indicia forming a chart generally designated 15 and relating to the purpose for which the device is designed, for example, the exhibition of data on lubrication or servicing of automobiles. A particular provision of this invention is the means for correlating and aligning these data with corresponding data on a separate movable element, such as an endless belt, to be described below, to give a predetermined relation as between the lubricating indicia, the locations in which particular lubricants are to be used; and the various makes, models and types of automotive equipment to which they may be applicable. In this example, to facilitate the function just outlined, there is provided a window or slot 16 extending transversely of sheet 14, as shown in Figures 1 and 2. Slot 16 may be covered by a narrow transparent sheet 17 of celluloid, glass, or the like, to prevent entrance of moisture or dirt, or the whole front of box 10 may be protected by a single large sheet of such material.

Immediately behind slot 16 is a guide or spacing bar 18, which is preferably hinged as at 19 to one side of box 10, so that it may be swung out of the way when the web, to be described below, 5 is to be removed or installed. The free end of bar 18 is preferably retained in clip 20 on the opposite side of box 10 when the bar is in its normal position (Figures 1 and 5). If desired, the hinge 19 could be replaced by a second clip 10 similar to 20, without departing materially from the invention or the arrangement illustrated.

A driving roller generally designated 21 is mounted at the upper end of box 10 and serves to support and control the endless belt or web 22 15 on which certain of the indicia or data to be exhibited and aligned are imprinted. Roller 21 may conveniently be made of a wooden or fibre cylinder 23, fitted with a flange 24 at each end, to prevent the web 22 from becoming misaligned. A rod 20 25 is axially fixed to one end of the cylinder 23, extends outwardly through a suitable hole in the side of box 10, and is bent as at 26 to form a crank or handle. A simple knob or disc could be substituted for crank 26 if desired. Sleeve 27, 25 which may be a short length of pipe, serves to space the cylinder 23 and crank 26 with regard to the side of box 10, as shown in Figure 3.

At the opposite end of cylinder 23 is an axial rod 28, slidably fitted in bore 29 and urged outwardly as by spring 30. The outer end of rod 28 passes through a suitable hole in the side of box 10, and is fitted with a shoulder 31, which bears against the side wall and serves to space and align the roller 21 in the box 10. The friction at 35 this point also serves to prevent undesired rotation of the roller 21 and consequent movement of the web 22, so that the indicia which are aligned with slot 16 will remain in the position to which they are adjusted.

Web 22 may be an endless belt, such as paper, or paper backed with cloth, and is imprinted with the desired indicia 32 to be aligned with slot 16, and data 15 as shown in Figure 1. The lower end or bight of web 22 is preferably retained or 45 guided and held taut by an idler roller 33. That roller may conveniently be made of a wooden cylinder 34, with two end flanges 35, and is provided with two axial pins 36, which latter may be received in guide slots or channels 37, at the sides 50 of box 10. The web 22 is spaced from the slot 16 by guide bar 18, which thus lies between the front and back turns of the web, and prevents the web from curling or buckling away from the slot, so that its visibility and alignment are not 55 impaired.

In operation, crank 26 is rotated by the operator, thus turning roller 21 and moving the endless web 22 until the desired indicia, as 32 are visible through slot 16 in sheet 14. That data may then 60 be observed in relation to the indicia 15, the operator thus receiving the information desired. To remove the web 22, the sheet 14 is first removed, as by dropping it downwardly from its normal position in groove 13. Guide bar 18 is lifted 65 from its retaining clip 20, thus permitting the rear turn of the endless web 22 to be withdrawn forwardly from the box 10, together with idler roller 33, after the latter's removal from channels 70 37. Rod 28 is pressed inwardly against spring 30 until it is free from its hole in box 10, where-

upon the roller 21 and/or web 22 may be withdrawn forwardly from the box 10.

It will be appreciated that with the disclosed elements of a master chart on which are grouped or spaced indicia relating to points of lubrication and the types and grades of lubricants to be used therein, combined with a movable element, such as the endless belt or web, on which are supplementary data as to types, models and years of the various automotive equipment which are to be 10 serviced, with keys or symbols relating to the data on the master chart, and with means for conveniently aligning and correlating the web with the chart so that the desired data and none other, may be placed in predetermined relationship and 15 be readily observable, and yet shielded and protected from dirt from handling or the weather, this invention represents a considerable improvement and advance over the known art in this 20 field.

Although a specific construction embodying this invention has been described and illustrated, it is to be understood that the invention is not limited to that specific device, and all such modifications and changes as come within the scope 25 of the appended claims are embraced thereby.

I claim:

1. A lubrication indicator comprising a frame, means on the face of said frame forming a chart having an exposed surface for receiving grouped 30 indicia representing parts of equipment to be lubricated, a slot in said chart, an endless web removably positioned behind said chart so that a designated portion thereof is visible through said slot, a driving roller for said web removably positioned in said frame, means on said roller extending outside of said frame for rotating said roller, an idler roller for holding said web taut removably positioned in said frame, removable means in said frame for holding said web close 40 to said slot, said web having designating indicia and lubricating indicia adapted to be observed through said slot to cooperate with the grouped indicia on said chart in aligned relation of chart and key to selectively exhibit predetermined relations between said indicia.

2. A lubrication indicator comprising a frame, means on the face of said frame forming a chart having an exposed surface for receiving grouped indicia representing parts of equipment to be 50 lubricated, a slot in said chart, an endless web removably positioned behind said chart so that a designated portion thereof is visible through said slot, a driving roller for said web removably positioned in said frame, said roller comprising 55 a cylindrical member and a slidably pivot therefor, said pivot adapted to project outwardly through said frame, and a spring adapted to urge said pivot into engagement with said frame, means on said roller extending outside of said 60 frame for rotating said roller, an idler roller for holding said web taut removably positioned in said frame, removable means in said frame for holding said web close to said slot, said web having 65 designating indicia and lubricating indicia adapted to be observed through said slot to cooperate with the grouped indicia on said chart in aligned relation of chart and key to selectively exhibit predetermined relations between said indicia.
